MULTIPLE-TUBE INSERTED PUMP.

Application filed May 2, 1927. Serial No. 188,254.

- An object of our invention is to provide a multiple tube inserted pump in which the sand, grit, and so forth, is effectively prevented from passing into the reciprocating elements of the pump.
- Another object is to force a quantity of fluid over the foot valve of the pump at each stroke of the pump, thereby keeping the valve clean and preventing the failure thereof.
- 10 A further object is to provide a multiple tube inserted pump in which the standing valve and traveling valve are only positioned at a short distance apart in the lower position of the pump.
- 15 Still another object is to provide a pump which is effective in operation, which will not become easily disarranged, and which may be removed from the well at the time of the removal of the sucker rods.
- 20 Other objects, advantages, and features of invention may appear from the accompanying drawing, the subjoined detailed description, and the appended claims.

In the drawing:

- 25 Fig. 1 is a fragmentary, longitudinal, sectional view of a three-tube type of pump.
- Fig. 2 is a fragmentary, longitudinal, sectional view of a two-tube pump.
- 30 Fig. 3 is a fragmentary, longitudinal, sectional view of the pump shown in Fig. 1, the view being above that shown in Fig. 1.
- Referring more particularly to the drawing:
- The usual well tubing 1 is provided with a
- 35 sleeve 2 at the lower end thereof in which a pump holding dog 3, of usual construction, is mounted. The dog 3 is of the type which locks in the sleeve 2 but which can be removed by a sharp pull on the sucker rods when it is
- 40 desired to remove the pump. The collar 4 is threaded onto the top of the dog 3 and a stationary sleeve 5 screws onto the outside of the collar 4. A foot valve cage 6 screws onto the collar 4 and is spaced from the sleeve 5. A
- 45 ball 7 is positioned in the cage 6 and the operation and object thereof will be further described.

- An inner stationary tube 8 screws into the cage 6 and extends to a collar 9 to which it is secured. The tube 8 screws into the inside of the collar 9 thus providing a space between the said tube and the stationary tube 5. A tube 10 screws onto the outside of the collar 9 and rises to a standing valve cage 11 which cage is provided with the usual ball 12. The tube 10 is threaded onto the usual cou-

pling 13 on which the cage 11 is also threaded.

A plunger 14 fits closely within the tube 5 and fits about the cage 11 and tube 10, but a space 15 is provided between the plunger and the tube 8 below the collar 9. A sleeve 16 screws onto the bottom of the plunger 14, said sleeve being adapted to engage the collar 9 when the pump is being removed from the well, thus removing the stationary tubes 10, 8 and 5 as well as the dog 3 and parts integral therewith.

A fluid passage 17 is provided between the cage 6 and tube 5, and ports 18 extend from the passage 17 through the wall of the cage 6, said ports being adjacent the ball 7. A traveling cage 19 is secured to the top of the plunger 14 and is provided with the usual ball 20. The sucker rods 21, which reciprocate the plunger 14, are secured to the top of the cage 19 and extend to the top of the well, in the usual manner.

In order that a constant upward pressure may be maintained on the dog 3, we provide a tapered ring 22 which sits closely within the tubing 1 and the tube 5 is provided with a tapered head 23 which sits within the ring 22, and a spring 24 bears against the ring 22 and against a shoulder or the top of tube 1 as shown in Fig. 3. Thus it will be seen that the spring 24 exerts a constant upward tension against the ring 22 and tube 5 which holds all of the stationary parts of the pump in proper position.

At times it will be desirable to provide a check valve above the cage 19 and in this event we thread the tube 5 into a coupling 25, the outer surface of said coupling being tapered to fit into the tapered ring 22. A screw seat 26 threads into the coupling 25 and into a cage 27 through which the sucker rods 21 extend. A collar 28 fits closely around the sucker rods 21 and is adapted to sit on the top of the screw seat 26, thus providing a check and preventing the liquid from moving downwardly in the tubing. On the up-stroke of the pump, the collar 28 lifts permitting the passage of fluid through the cage 27 and into the tubing 1.

In operation the plunger 14 is reciprocated by the rods 21 and on the up-stroke of the plunger the spaces 15, 17 are filled with liquid simultaneous with the filling of the pump. During this upward movement of the plunger, the ball 20 is seated and the balls 7, 12 are lifted permitting the filling of the pump. On the down-stroke the balls 7, 12

are seated and the ball 20 lifts, thus carrying the fluid into the tubing 1. During the down-stroke of the plunger the liquid in the chambers 15, 17 is forced through the ports 18 into the cage 6, thus washing over the ball 7 and removing all sand and sediment therefrom. Thus it will be seen that this ball is always clean and all sand, and so forth, removed from the seat thus assuring that it will be 10 properly cleansed at all times.

In the form of our invention shown in Fig. 2, the usual tubing 29 is provided with a sleeve 2 in which the dog 3 is mounted, as previously described. A foot valve cage 30 screws onto the top of the dog 3, said cage being provided with a ball valve 31. A stationary tube 32 screws into the cage 30 and a coupling 33 is mounted on the top thereof. A second stationary tube 34 threads into the 15 coupling 33 at the bottom and onto a standing valve cage 35 at the top, said standing valve cage being provided with a ball valve 36.

A plunger 37 fits closely within the tubing 29 and around the cage 35 and tubing 34. A fluid space 38 is provided between the inside of the plunger 37 and the outer surface of the tubing 32. A foot nipple 39 screws onto the bottom of the plunger 37, said nipple 25 being adapted to engage the coupling 33 to affect the removal of the pump from the well.

A fluid passage 40 is provided around the cage 30, said passage communicating with the chamber 38 by reason of the fact that the nipple 39 fits loosely about the tube 32. Ports 35 41 are provided in the wall of the cage 30, said ports being adjacent the ball 31 and the purpose of these ports will be further described. A cage 42 screws onto the top of the plunger 37 and the usual ball check 43 is 40 seated in the cage. The sucker rods (not shown) are secured to the cage 42 to reciprocate the plunger 37.

In operation as the plunger 37 is moved 45 upwardly the balls 31, 36 are unseated permitting the fluid to pass into the pump and the ball 43 remains seated. During the upward movement of the plunger the passage 40 and chamber 38 are filled with a liquid, and 50 on the down-stroke of the plunger the balls 31, 36 are seated while the ball 43 rises, thus moving the fluid into the tubing, and also during the down-stroke of the plunger the liquid in the passage 40 is forced through 55 the ports 41, washing over the ball 31 to thoroughly cleanse the same in a manner previously described under Fig. 1. At the extreme down-stroke of the plungers in both 60 Figs. 1 and 2, the standing valves 11, 35 are close to the traveling valves 19, 42, thus tending to force practically all of the liquid in the pump upwardly past the ball checks 20, 43.

Having described our invention, we claim:

1. A multiple tube inserted pump compris-

ing a stationary tube, a foot valve including a cage secured to the stationary tube, a standing valve positioned above said stationary tube, means connecting the standing valve and stationary tube, a plunger, said plunger 70 having a chamber therein, adapted to receive the liquid on the up-stroke of the pump, said foot valve cage having ports therein adjacent the bottom thereof through which liquid is adapted to be forced on the downstroke of 75 the plunger to wash over the foot valve.

2. A multiple tube inserted pump comprising a stationary tube, a foot valve cage on the bottom of said tube, retaining means depending from the foot valve cage, a standing 80 valve, means connecting said standing valve and stationary tube, a plunger, a traveling valve in said plunger, said traveling valve and standing valve being positioned close together in the lowered position of the plunger, 85 said plunger having a chamber formed therein, said foot valve cage having ports formed therein through which liquid is drawn on the up-stroke of the plunger, the liquid being forced through said ports and over the valve 90 on the downstroke of the plunger.

3. A multiple tube inserted pump comprising a holding dog secured in the well tubing, a foot valve cage secured to said dog, a stationary tube secured to said cage and rising 95 therefrom, a standing valve cage secured to the top of the stationary tube, said foot valve cage and standing valve cage having check balls therein, a plunger, a traveling valve in said plunger, said plunger having a liquid 100 chamber formed therein, said foot valve cage having ports therein adjacent the ball, said plunger being adapted to force liquid from the chamber through the ports on the downstroke thereof to wash over the ball. 105

4. In a multiple tube inserted pump comprising an outer stationary tube, means to removably secure said outer tube in the well, an inner stationary tube, a plunger reciprocating between said outer and inner tubes, a 110 head on said outer tube, and means yieldably engaging a ring engageable with said head to urge the outer tube upwardly and thus retain the same in the well.

5. A multiple tube inserted pump adapted 115 to be positioned in a well tubing comprising a dog removably secured in the well, an outer stationary tube secured to said dog, a plunger in said tube, a tapered ring closely fitting the well tubing, a tapered head on the outer tube 120 adapted to fit the ring, and a spring engaging said ring whereby the outer tube is urged upwardly.

6. In a multiple tube inserted pump comprising an outer stationary tube, means removably securing said tube in the well, tubing in which the pump is mounted, a tapered ring closely fitting the tubing, a check valve cage secured to said stationary tubing, said check valve cage fitting the tapered ring, a 125 130

spring bearing against the bottom of the tapered ring, a plunger in the tubing, a sucker rod secured to said plunger, and check means surrounding the sucker rod in the check valve

5 cage.

7. A multiple tube inserted pump adapted to be positioned in a well tubing, a retaining dog removably mounted in the tubing, a foot valve secured to said dog, a stationary tube

10 secured to the foot valve, a standing valve, means connecting said stationary tube and

standing valve, a plunger in said tubing, said plunger having a liquid chamber formed therein, said foot valve having ports formed therein through which liquid is adapted to be forced on the down-stroke of the plunger to cleanse the valve, and a check valve in said tubing above the plunger. ¹⁵

In testimony whereof, we affix our signatures.
